(57) **CLAIM**

The ornamental design for a control panel of a patient transport device having surface ornamentation, as shown and described.

DESCRIPTION

FIG. 1 is a right side elevational view of a control panel of a patient transport device having surface ornamentation illustrating an embodiment of our new design; FIG. 2 is a left side elevational view thereof; FIG. 3 is a front elevational view thereof; FIG. 4 is a rear elevational view thereof; FIG. 5 is a top plan view thereof; FIG. 6 is a bottom plan view thereof; FIG. 7 is a left, rear, top isometric view thereof; FIG. 8 is a left, rear, bottom isometric view thereof; and, FIG. 9 is a partially enlarged top plan view of FIG. 5 thereof. The broken lines in the drawings represent portions of the control panel of a patient transport device having surface ornamentation that form no part of the claimed design and are considered necessary to show the environment in which the design is associated.
